UNITED STATES PATENT OFFICE

GEORGE A. HERDTER, OF ST. ALBANS, NEW YORK, ASSIGNOR TO C. R. DANIELS INC., OF NEW YORK, N. Y., A CORPORATION OF NEW YORK

SEWING MACHINE

Application filed December 21, 1931. Serial No. 582,371.

This invention relates to sewing machines and particularly to machines using alternating presser feet which are used for stitching several layers of cloth. These alternating 5 pressers consist of two separate presser feet, one of which assists the drop feed in carrying the work forward for each stitch, while the other foot alternately rises and descends to hold the work. The present invention re- 10 sides in a form of presser foot which enables cordage or cylindrical bodies to be stitched to a flat fabric while insuring an even feed between the fabric and the cordage. This presser foot cooperates with the feed dogs 15 of the machine so that in the forward movement of the feed, the fabric and the cordage are moved to the same extent. For this purpose, the presser foot engages the cordage on the top by a non-slipping engagement dur- 20 ing the feeding movement so that as the cordage is stitched to the fabric a smooth, even surface is obtained without wrinkles.

This invention will be more particularly understood from the following specification 25 and the accompanying drawing, in which,

Fig. 1 is a front elevation of the vertical moving parts of the sewing machine head to which this invention is attached;

Fig. 2 is a plan view of the presser feet 30 sectioned on line 2-2, Fig. 1;

Fig. 3 is an elevation, partly sectioned, showing the presser feet in place during the stitching operation;

Fig. 4 is an elevation, partly sectioned, 35 with the needle withdrawn and the feed dogs at the start of the feed movement;

Fig. 5 is a sectional detail on line 5-5 of Fig. 4;

Fig. 6 is an elevation, partly sectioned, 40 showing the feed dogs at the end of the feed movement;

Fig. 7 is an elevation, partly sectioned, of the feed dogs in the lowered position, and

Fig. 8 is a fragmentary view of a portion 45 of canvas to which a rope has been directly stitched by the mechanism illustrated.

The presser foot which assists the drop feed comprises two parallel bars which are placed directly over the feed dogs and are 50 spaced apart by a pair of arch-shaped end

pieces through which the cordage passes and is guided. These arch-shaped end pieces are provided with adjustable points which project into the cordage when the feed movement is being made thereby insuring that the 55 comparatively stiff cordage shall feed at the same rate as the canvas to which it is to be stitched. When the feed movement is completed the cordage is released from these points and the presser foot returns by a 60 spring action to the starting position for another operation. The presser foot is provided with an aperture at the feed end through which the cordage passes and is maintained in alignment with the presser 65 foot.

In the drawing, 11 is the sewing machine head and 12 is the table. 13 is the feed presser foot which is operated by the stem 14, 15 is the holding presser foot operated by the 70 stem 16 and 17 is the needle stem carrying the needle 18. The needle feeds directly through a slot in the presser foot 15 and through the cordage 19 and the fabric 20, making the stitch as indicated at 23, Fig. 8. 75 The feed dogs are indicated at 21 and move forward in the slot 22 in the table of the machine, these dogs aligning with the parallel members 31 and 32 of the presser foot 13.

The sewing machine mechanism referred 80 to for operating the stems 14, 16, 17 and the feed dogs 21 corresponds with the commercial mechanism of class 7 machines manufactured by Singer Manufacturing Company 85 and further description of the mechanism used to operate these parts is not necessary in the present case.

The presser foot for the purpose of this invention comprises the parallel bars 31 and 32, Fig. 2, which are joined at the ends by the 90 arch-shaped portions 33 and 34 and on the top of each arch a pointed screw 35 is provided. This device is secured by the lug 36 to the operating stem 14 of the machine. At the feeding end of the presser foot a bar 37 95 is provided as indicated in Figs. 4 and 5 forming an aperture through which the cordage 19 is fed with the object of maintaining the cordage in alignment with the needle and the portion already stitched and preventing it 100

from passing under the ends of the bars 31 and 32 and thus interfering with the operation of the machine.

As shown in the drawing the bars 31 and 32 press the fabric against the feed dogs 21 and against the table 12. The presser foot 15 rests upon the cordage and moves up and down therewith.

In the feeding operation as indicated in Fig. 4 the feed dogs 21 are raised and the cordage 19 is forced into engagement with the pointed screws 35, the feed dogs then move over to the extent of slot 22 as indicated in Fig. 6, carrying with them the fabric 20 and the presser foot 13 with the screws 35 and the cordage 19. The feed dogs then move downward and the presser foot 15 acting on the cordage 19 releases it from the pointed screws 35 and permits the presser foot 13 to return by spring action to the position shown in Fig. 3, during the stitching operation and in position to feed the cordage for the next stitch.

As far as I am aware there has been no previous attempt to provide a sewing machine attachment that would directly stitch comparatively stiff cordage to fabric and provide for a uniform feed of the cordage and fabric. The pointed screws 35 acting upon the top of the cordage contribute materially to this result and are an important feature of my invention.

Having thus described my invention, I claim:

35

40

45

50

55

60

65

1. A presser foot for use in stitching cordage to fabric comprising a pair of parallel members resting on the fabric and connected by spaced, arched members through which the cordage passes and points on said arched members arranged to engage said cordage during the feed movement of the fabric and cordage. 70

2. A presser foot for use in stitching cordage to fabric comprising a pair of parallel members resting on the fabric, a pair of feed dogs aligning with said members, transverse members connecting said parallel members and below which the cordage passes, means for engaging said cordage with said transverse members during the feed movement of said dogs and means for disengaging said transverse members and cordage. 75 80

3. A presser foot for use in stitching cordage to fabric comprising a pair of parallel members resting on the fabric, a pair of feed dogs aligning with said members, means connecting said members and an aperture formed by said connecting means at the entering end of said presser foot through which the cordage passes and means for engaging the cordage and said connecting means during the feed movement of said dogs. 85 90

Signed at New York, in the county of New York and State of New York, this 30th day of November, A. D. 1931.

GEORGE A. HERDTER.
